UNITED STATES PATENT OFFICE.

FRANS JOHAN HENRIK RUSTIGE AND FELIX CONSTANTIN SANDSTRÖM, OF STOCKHOLM,
SWEDEN.

REGULATING HEATING SYSTEMS.

1,321,395.

Specification of Letters Patent. Patented Nov. 11, 1919.

Application filed February 18, 1915. Serial No. 9,049.

To all whom it may concern:

Be it known that we, FRANS JOHAN HENRIK RUSTIGE and FELIX CONSTANTIN SANDSTRÖM, subjects of the King of Sweden, residing 5 the former at Stora Essingen, Stockholm, Sweden, and the latter at Drottningholmsvägen 6, Stockholm, Sweden, have invented new and useful Improvements in Regulating Heating Systems, of which the following is 10 a specification.

In heating systems where a liquid, vapor, or gas in a heated condition circulates through pipes or conduits an automatic regulation according to the temperature required 15 in the surrounding localities of the supply of medium to the radiators from which the heat is delivered is always desirable. Hitherto it has been difficult to effect such an automatic regulation, because the apparatus sensible to 20 changes of the temperature now in use (thermostats of different kinds, based on the expansion of gases, liquids or solid bodies) generally have not been able to produce the great mechanical effect required for moving 25 the heavy valves by which the admission of the heat-conducting medium is regulated. For that reason it has been necessary to use special external sources of power for producing the regulating movement of such 30 valves, while only the releasing of them has been effected by the thermostats; this arrangement, however, has made the whole system rather complicated.

The present invention has for its object 35 to facilitate the use of the heat conducting medium itself as a thermostatically regulated source of power, by which the regulating devices of the heating system are controlled.

40 The invention generally consists in providing one or more devices for producing pressure waves in the heating fluid, which devices are arranged in the pipe system and controlling valves connected to the radiators, 45 which valves are actuated by the pressure waves during certain conditions, determined by the thermostats. By the term "pressure waves" we mean any temporary pressure change, positive or negative, slow or rapid 50 (shock-like).

The invention is illustrated by way of example on the annexed drawings.

Figure 1 illustrates diagrammatically a heating system according to the invention,

Fig. 1^a is a detail view on a larger scale of 55 a valve 18 of Fig. 1.

Fig. 2 is a central section of a device for producing pressure waves in the pipe-system,

Fig. 3 is a similar section of a valve, which 60 is controlled thermostatically and operates by means of such pressure waves,

Fig. 4 is a combination of the devices illustrated in Figs. 2 and 3 in such a manner that the pressure waves are produced even at 65 that part of the pipe system or conduit where they are used for the control of the valve, and

Fig. 5 is a modification of the combination last mentioned. 70

At one or more suitable points within a pipe or conduit heating system (Fig. 1) and preferably adjacent to the source of heat 17, there is arranged a device for the production of pressure waves in the system. 75 This may be accomplished for instance by periodically throttling the current of the medium in the system. In Fig. 1^a the active part of a mechanical device is diagrammatically represented by a damper 19, 80 turned by a motor, such as a clock mechanism or some other mechanism (not shown). Obviously, the device may be arranged in many different ways. Fig. 2 illustrates an automatic device for this purpose and which 85 is shown embodied in the system disclosed in Fig. 1. On the casing 1 of the regulating valve a diaphragm casing is fixed, which consists of two parts 3 and 4, between which a diaphragm 5 is arranged. The diaphragm 90 is pressed downward against the valve by means of a spring 6 but is also acted upon in the opposite direction by another spring 7, which in the drawing is illustrated as a wire. The space or chamber under the diaphragm communicates with the interior of the valve casing. The spring 7 is not directly fixed to the diaphragm, but passes loosely through openings in clamp 10 on it and also through an oblong opening in the 100 spindle of the valve 2.

The upper part of the diaphragm casing in the drawing consists of a container 13, the bottom of which forms the roof of the actual diaphragm casing, while the walls of 105 the container are formed of a cylindrical flange 12 on the said roof. 14 is a cover for the container. In the bottom of the said

container two ports are arranged with valves 15, 16 the one 15 of which is a regulating valve with a screw, and the other one 16 provided with a movable valve plate, opening inwardly in the direction against the diaphragm casing.

This device operates in the following manner: If the main valve 2 is open and a medium, for instance steam or water under pressure, is supplied in the direction of the arrow, that pressure becomes transmitted to the under side of the diaphragm, which thereby is raised together with the spring 7. When the central part of the spring has been forced by its central position, it rapidly springs the rest of the way by itself and carries with it the valve spindle, which has been at rest to that moment owing to the oblong form of the opening 11. The valve 2 thereby is rapidly closed (the situation shown in Fig. 2) and the pressure in the pipe at the right hand of it begins to fall. But this falling of the pressure under the diaphragm produces a sinking of the diaphragm and of the spring 7, which latter after a short period springs over to its former position and opens the valve 2.

In this way there are produced in the pipe system periodic changes of pressure, the frequency of which of course may be controlled by adjustment of the valve 15 upon which the upward speed of the diaphragm depends. For facilitating this control the space above the diaphragm as well as the container 13 may contain a liquid, which is throttled or checked by the small port in the said valve 15 with better effect than air or other gas. The sinking or downward motion of the diaphragm in the construction illustrated is principally dependent upon the valve 16, which is assumed to have a considerably larger port or passage than that of the valve 15, so that the sinking of the diaphragm is performed with considerably greater speed than the raising. In this way characteristic pressure waves can be produced in the pipe system, the nature of which waves may be varied in any desired way by means of suitable devices for controlling the movement of the diaphragm.

The regulating valve illustrated in Fig. 3 is designed to respond to the pressure waves created by the devices shown in Fig. 1^a and 2 to control the supply of the heating medium to its respective radiator. As shown diagrammatically in Fig. 1, the inlet of each of the radiators is provided with a regulating valve such as shown in Fig. 3. This valve also consists of a valve casing 21 with a valve 22 and a diaphragm 24 with its casing 23. Upon the diaphragm there is fixed a toothed body 20, in which catches a rocking double ratchet 25, both so constructed that in one position (shown in the drawing) of the ratchet only the raising of

the diaphragm and in the other position only its sinking is permitted. The ratchet 25 is governed by a springing toggle joint 26, which always maintains the ratchet in one of its outmost positions, and is connected to a diaphragm 27 in a chamber 30 which is provided with a wall 29 and communicates with a spiral pipe 28, containing a suitable liquid or gas.

When this spiral, which forms the thermostat proper, is heated above a predetermined temperature, the fluid contained therein is expanded and the diaphragm 27 is depressed. When the depression has proceeded to a certain point, the toggle joint 26 is reversed and the double ratchet 25 is thrown from the position shown in Fig. 3 to the opposite one. At the next decrease of the pressure in the pipe system, the diaphragm 24 can be lowered so that the valve 22 is closed. A subsequent increase of the pressure, however, cannot open the valve on account of the form of the teeth upon that side of the body 20 in which the double ratchet 25 now catches. But when the temperature in the locality in which the thermostat is situated has fallen so much that the toggle joint under the action of the thermostat again can reverse to the position shown in Fig. 3, the valve can open again and remains in that new position during the time when the double ratchet and the toggle joint maintain their positions. The motion of the valve is thus effected by the power source, represented by the pressure changes in the pipe system, under a minute control, however, of the thermostat, which need not develop any great power, especially as the reversing of the double ratchet 25 can take place while the diaphragm is not under an excessive force.

Instead of placing a device for producing pressure waves, for instance such as that illustrated in Figs. 1 and 2, at one or more relatively central places in the pipe system, and controlling valves acted upon by the pressure waves, for instance such as illustrated in Fig. 3, at every radiator where an automatic control is required, these devices may be combined in such a manner that the pressure waves are produced at the same place, where they are to be used for the regulation, for instance at one or more of the radiators. In such a case the two devices for the generation or production of the waves and for the control of the fluid or medium currents are combined in one apparatus so that they form a whole or unit. Such an apparatus is illustrated in Fig. 4. The difference between the two forms of apparatus illustrated in Figs. 2 and 4 is that the valve 15 which is adjustable by hand, as shown in Fig. 2, is according to Fig. 4 connected to a lever 31, controlled by a thermostat, formed by a bladder 32 and a long pipe 130

33, connected thereto. In the arrangement indicated in Fig. 4, the valve 2 in the main conduit and the check valve 16 in the roof of the diaphragm casing must be so designed 5 that the check valve opens when the diaphragm moves in a direction to close the valve 2 in the main conduit. This, of course, is the opposite of the operation of the construction of Fig. 2; where the arrangement 10 is such that the check valve opens when the main valve is opened by the diaphragm. If the check valve 16 of the apparatus of Fig. 4 were arranged to open in the same direction as the valve 2 in the main conduit, as is the case in Fig. 2, the valve 2 in Fig. 4 would remain open and the supply of heat would be increased and not decreased.

Fig. 5 illustrates an apparatus where the changes of pressure in the pipe system are produced at the place where the control or regulation takes place, for instance at a radiator; but said apparatus is constructed in such a manner that the regulating member 25 during each period of increased pressure measures and allows a predetermined quantity of heating medium to pass. For that purpose a diaphragm 5 is connected to a valve spindle 40 provided with two valves 41 and 42, closing against the valve seats 43 and 44 respectively. Between these two valves opens a conduit 45 from the space under the diaphragm 5. The space above the said diaphragm is arranged in the same manner as is represented in Fig. 4, viz. communicating with an open liquid container 13 by means of a regulating valve 15, controlled by a thermostat 33 by means of a lever 31 and also by means of an upwardly 30 opening valve 16.

When the diaphragm and valve are in their lowest position, the heating medium flows from the left hand side of the valve casing through the conduit 45 into the chamber beneath the diaphragm and raises the latter. During this movement, the diaphragm moves freely, independently of the position of the thermostat valve, as the valve 16 opens upwardly.

50 At a certain instant, the valve 41, 42 is reversed so as to occupy the position shown in the drawing. This is effected by means of the spring 7 in the same manner as described with reference to Fig. 2. Then the heating medium beneath the diaphragm begins to flow back through the conduit 45 to the right hand side of the valve casing. For each stroke of the diaphragm, a predetermined quantity of heating medium is 55 thus admitted through the valve, namely, the quantity received in the chamber below the diaphragm before the latter reaches its reversing position. Beyond that, only a small quantity can pass through in the very 60 instant of reversion. As the sinking mo-

tion of the diaphragm is minutely controlled by the thermostat, the quantity of heating medium admitted per unit of time is obviously also controlled.

In the construction last described the valve spindle is arranged to act against a fluid-resistance device 46 in which the movement of the liquid can be controlled by means of a screw 47 in such a manner that the movement of the valve becomes retarded. This arrangement principally has for its object to prevent the generation of disturbing sounds at the reversing of the valve, but it also may be used for contributing to a control of the quantity of heating medium transmitted through the valve, because the quantity of said medium directly passing through the valve during the reversing operation (which quantity at an instantaneous reversion generally is immaterial in comparison with the measured one) of course becomes larger when the valve movement is retarded, so that the ratio between the same and the quantity measured by the diaphragm will be increased. Moreover a control can be effected by means of the screw 48, acting upon the spring 49 which presses upon the diaphragm.

Obviously also in the apparatus illustrated in Figs. 3 and 5, other movable walls, for instance, pistons, may be substituted for the diaphragms.

Having now particularly described the nature of our invention and the manner of its operation, what we claim is:

1. In a heating system, the combination comprising a pipe system, means for creating waves of pressure in a heating medium in said pipe system, valves in said pipe system adapted to be opened and closed by said pressure waves and means for controlling the speed of opening and closing of said valves.

2. In a heating system, the combination comprising a pipe system, means for creating waves of pressure in a heating medium in said pipe system, valves in said pipe system adapted to be opened and closed by said pressure waves and thermostatic means for regulating the opening and closing of said valves.

3. In a heating system, the combination comprising a pipe system, means for producing waves of pressure in a heating medium in said pipe system, controlling means for the passage of said heating medium adapted to be operated by said pressure waves, and thermostatic means for regulating said controlling means.

4. In a heating system, the combination comprising a pipe system, means for producing waves of pressure in a heating medium in said pipe system, a movable wall, the one side of which is in contact with said heating medium, a valve member operatively

connected to said movable wall and controlling the passage of the heating medium, and thermostatic means for regulating the movements of said movable wall and valve member.

5. In a heating system, a pipe system, means for creating pressure waves in a heating medium in said system, and mechanism adapted to be operated by pressure changes in said pipe line, comprising a valve, a chamber in communication with the pipe line, a diaphragm in said chamber and operatively connected to said valve, a pawl and ratchet mechanism for controlling the movement of said diaphragm, and thermo-operated means for controlling said mechanism.
10. In a heating system, a pipe system, means for creating pressure waves in a heating medium in said system, and mecha-
15. In a heating system, a pipe system, means for creating pressure waves in a heating medium in said system, and mecha-

nism adapted to be operated by pressure changes in said pipe line, comprising a valve; a chamber in communication with the pipe line, a diaphragm in said chamber and operatively connected to said valve, a pawl and ratchet mechanism for controlling the movement of said diaphragm, a second diaphragm operatively connected to said mechanism, and a thermostat for actuating the second diaphragm for the purpose described.

In testimony whereof we have signed our names to this specification in the presence of two subscribing witnesses.
